(57) **CLAIM**

The ornamental design for a bag retraction with retrieval funnel, as shown and described.

DESCRIPTION

FIG. 1 is a front perspective view of a bag retraction with retrieval funnel, showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a top perspective view showing the bag retraction with retrieval funnel in use with a bag.

The broken lines in form of a bag attached to the front side of the article depict environmental subject matter and form no part of the claimed design. The remaining broken lines in the drawings depict portions of the bag retraction with retrieval funnel that form no part of the claimed design.
